UNITED STATES PATENT OFFICE.

MARTIN NYSTROM, OF CHICAGO, ILLINOIS, ASSIGNOR TO THE BRUNSWICK-BALKE-COLLENDER COMPANY, OF CHICAGO, ILLINOIS, & CORPORATION OF DELAWARE.

BRAKE MECHANISM FOR TALKING-MACHINES.

1,274,581.

Specification of Letters Patent.

Patented Aug. 6, 1918.

Application filed August 23, 1917. Serial No. 187,746.

To all whom it may concern:

Be it known that I, MARTIN NYSTROM, a citizen of the United States, residing at Chicago, in the county of Cook and State of Illinois, have invented certain new and useful Improvements in Brake Mechanism for Talking-Machines, of which the following is a specification.

This invention relates to talking machines and has for its primary object the provision of a brake mechanism for automatically stopping the record table when the reproduction has been completed.

A further object of my invention is the provision of a brake mechanism as above described which may be manually set to disengage the record table and either manually or automatically released, as desired.

Further objects and advantages of my invention will be apparent as it is better understood by reference to the following specification when read in connection with the accompanying drawing, illustrating the preferred embodiment thereof, in which—

Figure 1 is a plan view of a talking machine with my improved brake mechanism applied thereto;

Fig. 2 is a side elevation, partially in section, of the structure illustrated in Fig. 1;

Fig. 3 is an enlarged detail in perspective of the brake and latch therefor, and

Fig. 4 is a detail in section illustrating the pivot of the latch lever.

Referring to the drawing, 5 indicates a casing or support upon which the record table 6 is rotatably mounted to support the record 7. The table 6 is driven by suitable mechanism well-known in the art and therefore not illustrated and is preferably provided with a depending flange 8. A tone arm 9 is supported in movable relation to the sound amplifier 10 and is provided with a sound box 11 carrying a stylus 12 adapted to coöperate with the record 7 in a well-known manner to reproduce sounds recorded on the record.

A plate 13 is secured to the upper surface of the support 5 beneath the table 6. Pivoted at 14 on the plate 13 is a brake 15 having a manually operable handle 16 projecting beyond the periphery of the table 6 and an arm 17 carrying friction material 18 adapted to coöperate with the inner face of the depending flange 8 to prevent rotation of the table 6 when the friction material is in engagement with the flange.

The brake 15 is provided adjacent its pivot 14 with an abutment 19. A lever 20 is pivotally mounted on a stud 21 at about the middle of the plate 13. As will be seen by reference to Fig. 4 the stud 21 is fast to the plate 13 and a washer 22 is disposed between the plate and the lever 20. Thus the lever is lifted slightly from the plate 13 to prevent frictional engagement between the parts which might retard the rapid operation of the lever or increase the resistance to actuation thereof. Movement of the lever 20 is limited at one end by a stud 23 and at the other by a stud 24 and a keeper 25 on the plate 13.

The end of the lever 20 adjacent the brake 15 is provided with a toe 26 adapted to engage the abutment 19 and hold the brake 15 in inoperative position with the friction material 18 disengaged from the flange 8. A spring 27 connects the stud 28 on the lever 20 to a stud 29 on the brake 15 and tends to return the brake to its normal position with the friction material 18 in engagement with the flange 8. The brake 15 is provided with a cam surface 30 which engages a heel 31 on the end of the lever 20 opposite the toe 19. When the brake is moved to inoperative position the cam surface 30 thereon engages the heel 31 and positively actuates the lever 20 to move the toe 26 into engagement with the abutment 19.

A collar 32 on the tone arm 9 pivotally supports a member 33 having an operating handle 34 and a depending arm 35 which is adapted to contact with the tail 36 of the lever 20 when the tone arm is moved to the position indicated in dotted lines in Fig. 1 or when the reproduction is completed. The lever 20 is thus swung about its pivot to disengage the toe 26 from the abutment 19. The spring 27 immediately causes the brake 15 to rotate on its pivot carrying the friction material 18 into engagement with the flange 8, thus stopping rotation of the record table.

Obviously the point in the travel of the tone arm 9 when the reproduction is completed will vary with individual records and the member 33 is mounted to permit adjustment about its pivot. The pivotal connection offers sufficient resistance to insure operation of the lever 20 when the de-

105

110

pend ing arm 35 engages the tail 36 of the lever.

The brake 15 may be manually moved to operative position when desired without 5 waiting for the automatic disengagement of the toe 26 from the upright 19 by grasping the handle 16 and swinging the brake in a clockwise direction, viewing Fig. 1. The abutment 19 will cause the lever 20 to swing 10 in an anti-clockwise direction until the toe 26 is disengaged therefrom.

From the foregoing it will be readily understood that I have perfected a brake mechanism for talking machines which embodies relatively few and simple parts of inexpensive construction. My improved brake mechanism is adapted to accomplish the desired function of automatically stopping the talking machine at the conclusion 20 of the reproduction and is manually operable to either operative or inoperative position.

It will be further understood that various changes may be made in the form, construction 25 and arrangement of the parts without departing from the spirit and scope of the invention or sacrificing any of its material advantages, the form hereinbefore described being merely a preferred embodiment 30 thereof.

I claim:

1. In a mechanism of the character described, the combination of a pivoted brake adapted to engage a moving part of a talking 35 machine and having an abutment thereon, an elongated pivoted lever having a toe at one end adapted to engage said abutment, to hold said brake in inoperative position, a spring connecting said brake and lever and 40 tending to move said brake to operative position when said toe is disengaged from said abutment, adjustable means moving with the tone arm of the talking machine and adapted to engage and actuate the other end 45 of said lever, and a heel on said lever opposite said toe and disposed in the path of movement of said brake as the latter is moved to inoperative position to positively move said lever to engage said toe with said 50 abutment.

2. In a mechanism of the character described, the combination of a plate, a brake lever pivoted thereon and having an operating arm, an arm carrying friction means 55 adapted to engage a moving part of a talking machine and an abutment adjacent its

pivot, an elongated lever pivoted on said plate and spaced therefrom to prevent frictional engagement therewith, a toe on one end of said lever adapted to engage said 60 abutment, a spring connected to said brake on the side of its pivot opposite said abutment and to said lever, and adjustable means moving with the tone arm of the talking machine and adapted to engage and actuate 65 the other end of said lever to disengage said toe from said abutment.

3. In a mechanism of the character described, the combination of a plate, a brake lever pivoted thereon and having an operating arm, an arm carrying friction means adapted to engage a moving part of a talking machine and an abutment adjacent its pivot, an elongated lever pivoted on said plate and spaced therefrom to prevent frictional engagement therewith, a toe on one end of said lever adapted to engage said 70 abutment, a spring connected to said brake on the side of its pivot opposite said abutment and to said lever, adjustable means moving with the tone arm of the talking machine and adapted to engage and actuate 75 the other end of said lever to disengage said toe from said abutment, and a heel on said lever opposite said toe and disposed in the path of movement of said brake as the latter is moved to inoperative position to positively move said lever to engage said toe with said 80 abutment.

4. In a mechanism of the character described, the combination of a plate, a brake lever pivoted thereon and having an operating arm, an arm carrying friction means adapted to engage a moving part of a talking machine, and an abutment adjacent the 90 pivot, a single elongated lever pivoted on said plate and spaced therefrom to prevent frictional engagement therewith, a keeper on said plate embracing said lever to limit movement thereof, a stud on said brake opposite said abutment, a corresponding stud on said lever, a spring connected to said 95 studs, a toe on one end of said lever adapted to engage said abutment, and adjustable means moving with the tone arm of the 100 talking machine and adapted to engage and actuate the other end of said lever to disengage said toe from said abutment.

MARTIN NYSTROM.
